UNITED STATES PATENT OFFICE.

CHARLES L. RAYFIELD, OF CHICAGO, ILLINOIS, ASSIGNOR TO BENEKE & KROPP MANUFACTURING COMPANY, OF CHICAGO, ILLINOIS, A CORPORATION OF ILLINOIS.

CARBURETOR.

1,412,259.

Specification of Letters Patent. Patented Apr. 11, 1922.

Application filed December 16, 1916. Serial No. 137,373.

To all whom it may concern:

Be it known that I, CHARLES L. RAYFIELD, a citizen of the United States, and a resident of the city of Chicago, in the county of Cook and State of Illinois, have invented certain new and useful Improvements in a Carburetor; and I do hereby declare that the following is a full, clear, and exact description of the same, reference being had to the accompanying drawings, and to the numerals of reference marked thereon, which form a part of this specification.

This invention relates to an improved type of carburetor wherein means are provided for introducing raw fuel into the manifold of the engine from the carburetor irrespective of the adjustment of the throttle valve. The liquid fuel is supplied from the carburetor through openings at the pivotal connection of the throttle valve whereby under sudden suction drafts through the carburetor, fuel is pumped to an auxiliary reservoir and drawn therefrom due to the suction, into the carburetor, while under normal operating conditions said means serves only to draw a slight amount of air therethrough carbureted to some extent by the fuel.

It is an object therefore of this invention to construct a carburetor wherein means are provided operating normally to permit a slight flow of slightly carbureted air into the carburetor mixture flowing from the carburetor into the engine.

It is also an object of this invention to construct a carburetor provided with a float chamber and a mixing chamber together with an auxiliary inlet valve serving to operate a piston in a dash pot chamber to pump fuel into an auxiliary vented reservoir slightly above the normal level of fuel in the float chamber so that an elevation of the level of fuel to the auxiliary reservoir permits fuel to be drawn through a by-pass communicating with said reservoir and the mixing chamber of the carburetor at the throttle valve to enrich the mixture leaving the carburetor under sudden acceleration effects imposed upon the carburetor by the engine.

It is also an object of this invention to construct a carburetor provided with an auxiliary fuel dash pot chamber with a piston therein operable by sudden movement of the air valve, and with a fuel passage communicating with said dash pot chamber adapted to receive fuel pumped thereinto,

by movement of said piston, and leading into the pivotal mounting of the throttle valve of the carburetor to spray the fuel into the mixing chamber of the carburetor to enrich the mixture leaving the same.

It is finally an object of this invention to construct an improved type of carburetor construction operating efficiently to momentarily supply a spray of liquid fuel into the mixture leaving the carburetor.

The invention (in a preferred form) is illustrated in the drawings and hereinafter more fully described.

In the drawings:

Figure 1 is a side elevation of a carburetor embodying the principles of my invention.

Figure 2 is a central vertical section taken therethrough with parts shown in elevation.

Figure 3 is a detail section taken on line 75 3—3 of Figure 2, with parts omitted and parts shown in elevation.

Figure 4 is a detail section taken on line 70 4—4 of Figure 3.

Figure 5 is a detail section taken on line 80 5—5 of Figure 2, with parts shown in elevation.

Figure 6 is a detail section taken on line 6—6 of Figure 5.

Figure 7 is a reduced top plan view of 85 the carburetor.

As shown in the drawings:

The carburetor casing consists of a float chamber 1, and a mixing chamber 2, with the metal of the carburetor casing cored out 90 to form an inlet passage for air and fuel at one side of the mixing chamber denoted by the reference numeral 3. Said passage is formed between the float chamber and the mixing chamber, and with an extension of 95 the fuel float chamber therebeneath entirely filled with fuel and denoted by the reference numeral 4. A supplementary casing member 5, is secured at one side of the carburetor, having an air inlet passage 6, therethrough, communicating laterally in the side of the mixing chamber 2, opposite to said passage 3, and is provided with a dash pot chamber 7, formed at the lower end thereof.

A float 8, is mounted in the float chamber 1, and controls the inlet of fuel to the float chamber through an inlet pipe 9, and passages in the lower end of the float chamber in a well known manner, and since the details of construction and operation form no part of this invention, further description

thereof is not entered into. A fuel nozzle 10, is threaded into the casing partition wall between the chambers 3 and 4, to admit fuel from the chamber 4, into the air passage 3, and a needle valve 11, is slidably mounted through the top wall of the passage 3, to control the flow of fuel through said nozzle. A throttle valve 12, of the butterfly type, is pivotally mounted at the outlet of the mixing chamber 2, being secured upon a tubular shaft 13, with apertures or jets 14, through its hub communicating with the interior of the pivot shaft 13, for a purpose hereinafter pointed out.

15 An actuating lever 15, is rigidly secured upon the outer end of the pintle shaft 13, and connections are provided whereby the needle valve 11, for the fuel nozzle 10, is operated simultaneously with and in certain proportionate amounts with adjustment or movement of the throttle valve 12. For this purpose, a horizontal shaft 16, is pivoted on the casing of the carburetor, and is provided with a finger 17, engaging a notch 20 in the needle valve 11, shown in Figure 2, and the outer end of said shaft 16, carries a crank 18, one end of which is in contact with a cam 19, mounted upon the tubular throttle valve shaft 13, whereby the shaft 25 16, is operated and the finger 17, swung upwardly to elevate the needle valve when the throttle valve 12, is moved toward open position. This interconnection between the throttle valve and the needle, however, is 30 an old and well known construction in my types of carburetors, and further amplification of operation of the means of adjustment of this interconnection is not believed to be necessary.

35 40 Slidably mounted within the casing member 5, is a stem 20, on the upper end of which an air inlet valve closure 21, is secured, adapted to seat against an annular seat member 22, threaded adjustably into the upper end of the casing 5, and with an apertured piston 23, secured upon the lower end of said stem movable within the dash pot chamber 7. A movable disk closure 23^a, is slidably mounted beneath the piston 45 50 55 60 65 70 75 80 85 90 95 100 105 110 115 120 125 130 135 140 145 150 155 160 165 170 175 180 185 190 195 200 205 210 215 220 fuel in the pipe 31, being the same as that within the float chamber 1.

However, with a sudden opening of the throttle valve to accelerate the engine, a sudden and intense draft is created through the carburetor, causing the air valve 21, to be drawn downwardly thereby depressing the piston 23, and forcing the fluid upwardly through the pipe 31, into the auxiliary reservoir 32, wherein the level rises above the lower end of the pipe 34, communicating into the lower end of the reservoir. Due to the adjustment of the throttle valve shaft 13, as the throttle valve is thrown into wide open position, complete communication is established between the pipe 34, and the interior of the tubular throttle valve shaft so that the draft in the carburetor is exerted through the pipe 34, to draw the fluid upwardly from the auxiliary reservoir 32, spraying the fuel through the orifices 14, in the hub of the throttle valve. This supply of liquid fuel into the mixture leaving the carburetor serves to enrich the mixture so that rapid acceleration of the engine even under load may take place. The depression of the piston 23, injects a supply of fuel through the nozzle 36, into the air passage 6, of the carburetor, at the same time that the fuel is supplied to the reservoir 32, and if the throttle remains open, the continuing draft through the carburetor will hold the air valve 21, open and the piston 23, depressed any fuel remaining in the reservoir 32, after the initial depression of the piston 23, will be gradually dissipated by the draft through the pipe 34, and the drainage back through the pipe 31, thus affording for a limited time after the sudden opening of the valve 12, an enrichment of the mixture supplied by the carburetor so as to insure the engine picking up speed. If, after the sudden opening of the throttle 12, it is immediately returned to a less open position, the draft of air through the carburetor is diminished and the valve 21 and piston 23 moved upwardly, and the retraction of the piston tends, on account of the passages through the piston being restricted, to withdraw the fuel from the reservoir 32, and prevent an accumulation of fuel therein. After the movable members of the carburetor have assumed their new adjusted position determined by the wide open adjustment of the throttle valve, sufficient fuel will be supplied for proper carburation of the air entering the different portions of the carburetor to supply the proper fuel mixture to efficiently operate the engine. It is evident that a sudden opening of the throttle valve causes the fuel to be supplied at three different points in the carburetor. The downward movement of the piston 23, serves to force fuel from the dash pot upwardly and through the orifices of the throt-

tle valve, as described, the downward movement of said automatic air valve 21, which operates the piston serves to depress the metering pin 37, to open the auxiliary fuel nozzle 36, and the actuation of the throttle valve due to the interconnection thereof with the needle valve 11, serves to elevate the needle valve so that a greater supply of fluid is admitted as the throttle opens.

I am aware that various details of construction may be varied through a wide range without departing from the principles of this invention, and I therefore do not purpose limiting the patent granted otherwise than necessitated by the prior art.

I claim as my invention.

1. In a carburetor of the class described, a float chamber, a mixing chamber, a throttle valve in the mixing chamber, spray apertures in the throttle valve, a vented auxiliary fuel chamber connected with the fuel chamber and on a higher level than the normal level of fuel in the float chamber, an air valve operated mechanism for forcing fuel into the auxiliary fuel chamber, and means connecting the throttle valve and the auxiliary chamber below the vent therein.

2. In a carburetor of the class described, a float chamber, a mixing chamber, a throttle valve for said mixing chamber having a plurality of spray apertures in its walls, a dash-pot chamber connected with the float chamber, a piston therein, an air valve mechanism connecting the air valve and piston to move together, an auxiliary fuel chamber connected with the dash-pot chamber and on a higher level than the normal level of fuel in the float chamber, said fuel chamber having an air aperture therein, and means affording communication between the throttle valve and the auxiliary chamber below the air aperture.

3. In a carburetor, the combination of a casing having a float feed chamber and an air passageway to which fuel is supplied from the float feed chamber, an auxiliary chamber extending above the level of the fuel in the float chamber, an automatic air valve adapted to pump fuel from the float chamber to the auxiliary chamber, an outlet from the auxiliary chamber to the air passageway from a point in said chamber above the level of the fuel in the float chamber, and means for preventing increase in pressure in the auxiliary chamber so that the fuel is drawn through said outlet entirely by suction.

In testimony whereof I have hereunto subscribed my name in the presence of two subscribing witnesses.

CHARLES L. RAYFIELD.
